UNITED STATES PATENT OFFICE.

PAUL EHRLICH, OF FRANKFORT-ON-THE-MAIN, BAPTIST REUTER, OF HÖCHST-ON-THE-MAIN, AND PAUL KARRER, OF FRANKFORT-ON-THE-MAIN, GERMANY, ASSIGNORS TO FARBWERKE VORM. MEISTER LUCIUS & BRÜNING, OF HÖCHST-ON-THE-MAIN, GERMANY, A CORPORATION OF GERMANY.

ARSENO-METAL PREPARATIONS AND PROCESS OF MAKING SAME.

1,091,881.

Specification of Letters Patent. Patented Mar. 31, 1914.

No Drawing.

Application filed January 25, 1913. Serial No. 744,225.

To all whom it may concern:

Be it known that we, PAUL EHRLICH, M. D., professor of medicine, a citizen of the Empire of Germany, residing at Frankfort-on-the-Main, Germany, BAPTIST REUTER, Ph. D., chemist, a citizen of the Empire of Germany, residing at Höchst-on-the-Main, Germany, and PAUL KARRER, Ph. D., chemist, a citizen of the Republic of Switzerland, residing at Frankfort-on-the-Main, Germany, have invented certain new and useful Improvements in Arseno-Metal Preparations and Processes of Making Same, of which the following is a specification.

15 We have found that arseno compounds containing the radical

20 when combined with salts of metals such, for instance, as gold, platinum, palladium, copper, silver, form addition products wherein the metal is firmly coupled.

The process in question consists in combining the said arseno compounds with metallic salts in solution. The new compounds thus produced separate directly, or they may be isolated by precipitation, or obtained by evaporation. The new products constitute preparations of great value for therapeutic purposes, as they unite the action of the arseno compounds with that of the metal salts and thereby become more efficacious.

25 The arseno compounds which can be used in this process comprise not only the derivatives of the arsenobenzene, but also those which contain the radical above indicated, combined by the As^{II} with an aliphatic or inorganic residue, and which can be produced for instance by reducing a mixture of an aromatic arsionic acid, or an aromatic arsenoxid, and an aliphatic arsionic acid, or an inorganic arsenic compound. There may be obtained with arsionic acid, for instance, compounds containing two and more atoms of arsenic. These compounds are hereafter called "poly-arseno compounds" (see the following Examples XV-XVII).

30 The same metal compounds can be obtained by carrying out the manufacture of the arseno-metal preparations and of the arseno compounds in a single operation. For this purpose the compounds from which the arseno compounds are obtained by reduction, are reduced in presence of the metal salts (see Examples XVIII-XXI given hereafter).

35 The new products, in general, are readily soluble in water, methyl alcohol, diluted alkalis and hydrochloric acid, but insoluble or scarcely soluble in ether and benzene.

40 The following examples illustrate more particularly the invention, but in no way limit it:

Example I: 2 cc. of an aqueous solution of auric chlorid of 10 per cent. strength are introduced into 5 cc. of an aqueous solution of 5 per cent. strength of the dihydrochlorid of 4,4¹-dioxy-3,3¹-diaminoarsenobenzene. 45 Thus, a clear dark-brown solution of acid reaction is formed, from which, on addition of excess of alkali, no auric hydroxid separates, and from which, after treatment with alkali, no gold can be isolated either 50 by formaldehyde or by hydrosulfite. By evaporating this solution in a vacuum, or by adding to it a mixture of alcohol and ether, or of alcohol and acetone, solid products are obtained which, on addition of water, yield 55 clear solutions having properties similar to those of the original solution.

Example II: 2 cc. of a solution of the sodium salt of auric oxid of 10 per cent. strength are introduced into 5 cc. of an aqueous solution of 5 per cent. strength of the disodium salt of diaminodioxyarsenobenzene, whereby a dark-brown solution of an alkaline reaction is formed, wherein the gold cannot be precipitated by a reducing agent, or precipitated by sodium sulfid. By evaporating the solution in a vacuum or adding to it a considerable quantity of alcohol or of alcohol and ether, solid products are obtained readily soluble in water.

Example III: 3 cc. of an aqueous solution of platinic chlorid of 10 per cent. strength are introduced into 5 cc. of a solution of 5 per cent. strength of dihydrochlorid of diaminodioxyarsenobenzene, whereby a light-brown solution is produced which behaves

toward precipitating agents like the solution described in Example I.

Example IV: 2 cc. of a solution of platinic chlorid of 10 per cent. strength, previously made alkaline by caustic soda lye, are introduced into 5 cc. of a solution of 5 per cent. strength of the disodium salt of diaminoxyarsenobenzene in water, whereby a light-brown solution is produced which behaves toward precipitating agents like that described in Example II.

Example V: 3 parts of sodium formaldehyde sulfoxylate of diaminodioxyarsenobenzene, of the formula:

15

20

dissolved in a small quantity of water, are mixed with 0.7 part of cupric chlorid $\text{CuCl}_2 \cdot 2\text{H}_2\text{O}$, also dissolved in water. On pouring the mixture into a mixture of alcohol and ether, the addition-product is precipitated in the form of a yellow voluminous powder, dissolving in water to a yellowish-red solution. In this compound the copper cannot be detected by means of the usual reagents, and it is only by boiling that the compound is gradually decomposed.

Example VI: 3 parts of sodium formaldehyde sulfoxylate of diaminodioxyarsenobenzene are dissolved in a small quantity of water and there is then gradually added, while continually stirring, a solution of 0.77 part of silver nitrate in 20 parts of water. By adding a mixture of alcohol and ether, the compound is precipitated in the form of a black powder, which dissolves in water to a clear solution. The aqueous solutions show an intense fluorescence.

Example VII: A diluted aqueous solution of about 0.25 gram of auric chlorid is introduced drop by drop into a solution of 1.5 grams of arsenophenylglycin of the formula:

55

60

in water until a precipitate is formed. To this mixture is added alcohol and ether, whereupon the addition compound precipitates in the form of a grayish-yellow powder. It is readily soluble in water and

alkalis, the gold being very firmly bound in it.

Example VIII: 0.8 gram of auric chlorid dissolved in 5 cc. of water are introduced into a concentrated aqueous solution of 1 gram of the sodium salt of 4,4'-dioxyarsenobenzene. On evaporating the solution in a vacuum, or adding alcohol and ether, a brownish-black addition-product is obtained which readily dissolves to a brownish-red solution.

Example IX: 1 gram of hydrochlorid of 3,3'-diamino-4,4'-dioxyarsenobenzene dissolved in 10 cc. of methyl alcohol is mixed with some drops of methyl alcohol solution of hydrochloric acid and then combined with a solution of 0.56 gram of corrosive sublimate in 10 cc. of methyl alcohol. The color of the solution turns from light-yellow to dark-orange. By adding ether the addition compound is precipitated in the form of a light-yellow powder. It is very readily soluble in glycerin, ethylene glycol, methyl alcohol; also soluble in acidified solution of potassium iodid. It is decomposed by water, particularly easily when warmed.

Example X: 1 gram of hydrochlorid of diaminodioxyarsenobenzene, dissolved in 10 cc. of methyl-alcohol, is mixed with a solution of 0.36 gram of silver nitrate in methyl alcohol, whereby a reddish-brown solution is obtained. On adding ether, the addition product is precipitated in the form of a brownish-yellow powder. It is very readily soluble in water, methyl alcohol, glycerin, etc. The solutions do not show any traces of silver ions, and by adding a reducing agent no silver is isolated. The compound contains one molecular proportion of diaminodioxyarsenobenzene to one molecular proportion of silver nitrate.

Example XI: 1 gram of hydrochlorid of diaminodioxyarsenobenzene is combined, as indicated in Example X, with 0.72 gram of silver nitrate. The precipitate thus produced is of a dark-brown color and dissolves in water to an intense-reddish-brown solution. The compound contains one molecular proportion of diaminodioxyarsenobenzene to 2 molecular proportions of silver nitrate.

Example XII: A solution of 3 grams of hydrochlorid of diaminodioxyarsenobenzene in 15 cc. of methyl alcohol is acidified, with a few drops of hydrochloric acid dissolved in methyl alcohol, and into the solution is introduced a solution of 1.07 grams of cupric chlorid, $\text{CuCl}_2 \cdot 2\text{H}_2\text{O}$, in 10 cc. of methyl alcohol. The mixture assumes a brownish-red color, and after a short time the addition-product crystallizes. When dry, it forms an orange-yellow powder, readily soluble in water, glycerin and ethylene glycol. By addition of caustic alkali to the cold aqueous solution, cupric hydroxid is precipitated, and it is only on heating that

cupric oxide separates. The compound thus formed contains one molecular proportion of diaminodioxyarsenobenzene to one molecular proportion of cupric chlorid.

Example XIII: A solution of 3 grams of hydrochlorid of diaminodioxyarsenobenzene in 20 cc. of methyl alcohol is run into a solution of 1.24 grams of cuprous chlorid in hydrochloric acid dissolved in methyl alcohol, and the addition-product is precipitated by adding ether. The compound thus obtained forms a brick-colored powder, readily soluble in water, and contains one molecular proportion of diaminodioxyarsenobenzene to one molecular proportion of cuprous chlorid.

Example XIV: 1.5 grains of hydrochlorid of diaminodioxyarsenobenzene dissolved in methyl alcohol are introduced into a solution of 0.55 gram of silver nitrate in methyl alcohol and there is then added a solution of 1 gram of auric chlorid in methyl alcohol. On addition of ether the compound is precipitated as a brownish-red powder. It is readily soluble in water, glycerin, etc., and contains one molecular proportion of diaminodioxyarsenobenzene to one molecular proportion of silver nitrate and to one molecular proportion of auric chlorid.

A "poly-arseno compound," such as has been referred to above and as used in the following examples, is obtained by reducing a solution of 23.3 grams of 3,4-amino-oxyphenylarsinic acid and 13 grams of sodium arsenite by means of sodium hydrosulfite in diluted aqueous solution; it is an orange-yellow powder readily soluble in diluted caustic soda lye as well as in diluted hydrochloric acid. It contains about 49 per cent. of arsenic, the arsenic atom of the arsenite being linked to the arsenic atom of the arsionic acid, thus forming the group:

Example XV: 3 grams of the aforesaid "poly-arseno compound" are dissolved in 60 cc. of methyl alcohol and 1.5 cc. to 2 cc. of hydrochloric acid (spec. gravity 1.12), and into the clear liquid is introduced a solution of 1 gram of cuprous chlorid in 2.5 cc. of hydrochloric acid (of spec. gravity 1.12) and 20 cc. of methyl alcohol. The liquid becomes deep dark-red, and on pouring it into several times its volume of ether, the double compound can be precipitated. When dry, it forms a light-brown powder soluble in methyl-alcohol and water. The solution can be made alkaline with caustic soda lye without precipitation of cuprous oxid. On adding sulfuric acid, a difficultly-soluble sul-

fate is precipitated from the aqueous solution of the substance.

Example XVI: 3 grams of the aforesaid "poly-arseno compound" are dissolved in 60 cc. of methyl alcohol and 1.5-2 cc. of hydrochloric acid (of spec. gravity 1.12), and into the clear liquid is introduced a solution of 2.7 grams of mercuric chlorid in 20 cc. of methyl alcohol, whereupon the liquid becomes at once an orange magma of the compound. In order to facilitate its filtration, some ether is added, and after filtration, the mass is washed with ether and dried. Thus an orange powder is obtained, which is insoluble in water and methyl alcohol and on adding aqueous caustic soda lye decomposes while becoming black.

Example XVII: 3 grams of the aforesaid "poly-arseno compound" are dissolved in 60 cc. of methyl alcohol and 1.5-2 cc. of hydrochloric acid (of spec. gravity 1.12) and to the clear liquid a solution of 0.85 gram of silver nitrate in 5 cc. of water and 20 cc. of methyl alcohol is added. The mixture is of a deep dark brownish-orange color; there is no substantial precipitation of silver chlorid and no reduction of the silver salt. After having filtered any very small precipitate which may have formed, the liquid is poured into about 500 cc. of ether. The compound thus precipitated is filtered, washed with ether and dried. It forms a brown powder, readily soluble in methyl alcohol and soluble in water; its aqueous solution can be rendered alkaline by adding caustic soda lye without any precipitation.

Example XVIII: 10 grams of 3-amino-4-oxyphenyl-1-arsinic acid are dissolved in 100 cc. of water and 43 cc. of 2N hydrochloric acid. There are then added 3.64 grams of cupric chlorid $CuCl_2 \cdot 2H_2O$ dissolved in a small quantity of water, and the whole is heated to about 50° C. Into this mixture is introduced a solution, heated to 50° C., of 50 grams of hydrosulfite in 150 cc. of water, and after adding 43 cc. of 2N. caustic soda lye, the mixture is stirred for several hours at 50° C. The brownish-red precipitate thus produced is filtered and well washed with water. The product is readily soluble in diluted hydrochloric acid and caustic soda lye.

Example XIX: 6 grams of 3-amino-4-oxyphenylarsenoxid are dissolved in an excess of hydrochloric acid and 2.5 grams of cupric chlorid $CuCl_2 \cdot 2H_2O$ added, and this mixture is mixed with a solution of 8 grams of stannous chlorid in concentrated hydrochloric acid, whereupon the hydrochlorid of the metal-salt compound immediately separates.

Example XX: 3 grams of 3-amino-4-oxyphenylarsenoxid are dissolved in the calculated quantity of diluted hydrochloric acid, and there are added, first a solution of 2.25

grams of auric chlorid in water, and then, in a single dose, a solution of 30 grams of hydrosulfite. The metal-salt compound of 3.3¹-diamino-4.4¹-dioxyarsenobenzene with 5 auric chlorid separates at once in the form of a golden yellow precipitate.

Example XXI: 2 grams of p-aminophenylarsenoxid are dissolved in the calculated quantity of diluted hydrochloric acid, 10 and there are added, first 1 gram of platinic chlorid dissolved, in water, and then in a single dose, a solution of 30 grams of hydrosulfite in water. The addition-product of the arseno compound and platinic 15 chlorid separates at once. It forms a yellowish-brown body, readily soluble in pyridin and N. hydrochloric acid.

Having now described our invention, what we claim is:

20 1. The process of manufacturing arseno-metal preparations, which consists in combining arseno compounds containing the radical

30 with salts of heavy metals.

2. The process of manufacturing arseno-metal preparations, which consists in combining arseno compounds containing the radical

40 with salts of heavy metals in solution.

3. The process of manufacturing arseno-metal preparations, which consists in combining with salts of heavy metals in solution, arseno compounds containing the radical

50 in conjunction with an aromatic complex of atoms coupled with the arsenic atom As^{II}-

4. The process of manufacturing an arseno preparation, which consists in combining the hydro-chlorid of 3.3¹-diamino-4.4¹-dioxyarsenobenzene with cuprous chlorid.

5. As new products, arseno-metal preparations containing the radical

and a heavy metal, said metal being bound in the form of a complex salt and not being detectable by the usual analytical reagents; 70 the preparations being readily soluble in water, methyl alcohol, diluted alkalis and hydrochloric acid, but substantially insoluble in ether and benzene.

6. As a new product, a preparation containing the radical

80 and copper, the copper being bound in the form of a complex salt and not being detectable by the usual analytical reagents, 85 said preparation being readily soluble in water, methyl alcohol, diluted alkalis and hydrochloric acid, but substantially insoluble in ether and benzene.

90 7. As a new product, a preparation consisting of 3.3¹-diamino-4.4¹-dioxyarsenobenzene combined with cuprous chlorid, in a complex form, the copper not being detectable by the usual analytical reagents, said 95 preparation being readily soluble in water, methyl alcohol, diluted alkalis and hydrochloric acid, but insoluble or scarcely soluble in ether and benzene.

95 In testimony whereof, we affix our signatures in presence of two witnesses.

PAUL EHRLICH.
BAPTIST REUTER.
PAUL KARRER.

JEAN GRUND,
CARL GRUND

Correction in Letters Patent No. 1,091,881.

It is hereby certified that in Letters Patent No. 1,091,881, granted March 31, 1914, upon the application of Paul Ehrlich, of Frankfort-on-the-Main, Baptist Reuter, of Höchst-on-the-Main, and Paul Karrer, of Frankfort-on-the-Main, Germany, for an improvement in "Arseno-Metal Preparations and Processes of Making Same," an error appears in the printed specification requiring correction as follows: Page 3, line 17, for the word "grains" read *grams*; and that the said Letters Patent should be read with this correction therein that the same may conform to the record of the case in the Patent Office.

Signed and sealed this 6th day of July, A. D., 1915.

[SEAL.]

R. F. WHITEHEAD,
Acting Commissioner of Patents.
